UNITED STATES PATENT OFFICE.

JOSEPH D. HOBBS, OF MEDIAPOLIS, IOWA.

IMPROVEMENT IN COMBINED SQUARE AND BEVEL.

Specification forming part of Letters Patent No. **222,354**, dated December 9, 1879; application filed October 9, 1879.

To all whom it may concern:

Be it known that I, JOSEPH D. HOBBS, of Mediapolis, Des Moines county, Iowa, have invented a new and useful Improvement in Patterns, of which the following is a specification.

The object of my invention is to provide a method whereby a given slant or angle may be transferred from the given object to any object of measurement in mechanical constructions alone.

The invention consists of a tri-square-shaped tool, with arms E and K of corresponding length, with a tongue or drop-extension, L, to the graduated arm K, nearly equal in length to the arm E, and forming, with the arm E, a perfect square, said tongue or drop-extension L being the third arm of the tri-square. The arm E is scalloped at the end. The arm K is traversed nearly its entire length by a narrow slot, in which works a thumb-screw bolt, movable along the slot. This thumb-screw bolt clasps a simple movable bar or yoke, H, about two-thirds of its length from the end, making said bar or yoke H correspond with the arm E. This movable bar or yoke H may be made to register any slant or angle on the graduated arm K by adjusting it by means of the thumb-screw bolt. The object of this device is to transfer given angles or slants in mechanical structures to any desired object of measurement after having obtained the given angles or slants by means of a square or bevel.

The operation in a particular case, as applied to hub-mortises, is as follows: Take the improved bevels, as shown and described in my previous patent, No. 213,987, of April 8, 1879, insert the two arms in the mortise, fasten them at the right slant, then apply the arms of the

bevel with the slant thus obtained to the arm E and the bar or yoke H of the pattern; adjust the bar or yoke H, by means of the thumb-screw bolt, so as to make the arm E and the bar or yoke H correspond with the arms of the bevels. Thus the slant of the mortise is transferred to the pattern and registered by the bar or yoke H on the graduated arm K. Then put the pattern on the spoke, and make the spoke correspond exactly with it. In this way the spoke is made to fit without danger of mistake, and does away with the old block system.

Again, to obtain the slant by use of the pattern alone, place the bar or yoke H at the base of the object of measurement, then loosen the thumb-screw bolt, move the tongue or drop-extension L till it corresponds in slant with the slant of the object of measurement, tighten the thumb-screw, and the proper slant may then be obtained and transferred to the desired object.

What I claim is—

The tri-square, with graduated arm traversed nearly its entire length by a narrow slot, in which works a thumb-screw bolt, which bolt clasps a movable bar or yoke, capable of registering on the graduated arm by proper adjustment with the corresponding arm any slant or angle, by means of the graduated arm and the thumb-screw bolt, and the tongue or drop-extension to the graduated arm, making, with the corresponding arm above, a perfect square, as above described.

JOSEPH D. HOBBS.
